W. Henry Walker,

Inventor:

William Hughes.
By his attorney.

Anderson & Myers.

UNITED STATES PATENT OFFICE.

WILLIAM HUGHES, OF MINERVA, OHIO.

ADJUSTABLE SCREEN-DOOR.

SPECIFICATION forming part of Letters Patent No. 394,651, dated December 18, 1888.

Application filed August 1, 1888. Serial No. 281,665. (No model.)

To all whom it may concern:

Be it known that I, WILLIAM HUGHES, a citizen of the United States of America, residing at Minerva, in the county of Stark and 5 State of Ohio, have invented certain new and useful Improvements in Adjustable Screen-Doors, of which the following is a specification, reference being had therein to the accompanying drawings.

10 My invention relates to adjustable screen-doors; and it has for its object to produce doors of this class which will be capable of adjustment to fit openings of various sizes.

The invention will first be described in 15 connection with the accompanying drawings, and then pointed out in the claims.

Figure 1 is a front elevation, partly broken out, of a door expanded to full width and showing the auxiliary screen in position. 20 Fig. 2 is a front elevation of a door adjusted to its narrowest limit and without the auxiliary screen. Fig. 3 is a vertical section of the door, taken on the line *x x*, Fig. 1, looking in the direction of the arrow. Fig. 4 is a trans- 25 verse section of the door, taken on the line *y y*, Fig. 1. Fig. 5 is a plan view of the auxiliary screen.

Referring to the drawings, A A' are the rigid side rails of the door, which are made 30 the length of doors of the largest size common in dwellings, the distance apart at which they are framed together permitting them to come within about half an inch of covering the width of the smallest common-sized doorways. I prefer to make rail A about five 35 inches in width and one inch in thickness, and rail A' about one inch in width and three-quarters of an inch in thickness.

B B' represent the cross-rails, of the same 40 general thickness as rail A and mortised into the side rails, rail A' coming flush on the rear or inner side with the other parts of the door, the upper cross-rail, B, being placed at a height suitable for the smaller-sized doors. 45 The cross-rails are reduced to the same thickness as rail A' for a short distance inward from said rail by being cut away on the front side, leaving a shoulder, *s*, and in this reduced portion, and for several inches beyond 50 the shoulder, there is cut a channel, *c*, for a purpose hereinafter explained.

C is the wire-cloth screen, secured in grooves in the frame, preferably near the rear side, in the ordinary manner.

D represents a sliding side rail, which is of 55 L shape in cross-section and made, preferably, by nailing together two wood strips, 1 and 2, in such manner as to bring the outer edge of the former flush with the outer side of the latter, the width of strip 1 being equal to 60 the width of side rail A, and the width of strip 2 equaling the thickness of rail A'. Strip 1 is slotted transversely at 3 3 and is loosely attached to rail A' by means of headed screw-threaded studs 4, passing through the 65 slots and through the said rail, and nuts 5, screwed onto the studs. When in place, the sliding side rail D passes freely over the side rail A' and the adjoining ends of the cross-rails B B' until arrested by the shoulders *s* on 70 the latter, in which position the strip 2 of rail D, which is about one-half inch thick, will be brought close against the outer side of side rail A', thus widening the door that much and covering the full width of the 75 smallest common-sized doorway, and as I make the strip 1 about one-quarter of an inch thick the sliding side rail will lie flush with the other rails of the door. It will be evident that by means of this sliding side rail the 80 door can be adjusted to any greater width within the limits of the length of the slots 3 3.

For the purpose of steadyng the sliding rail in its movements, and also for relieving strip 1 of said rail from a portion of the strain 85 at the inner ends of the slots when the sliding rail is adjusted at its outer limit, I secure arms *d* to the under side of said strip, which arms are of a size to fit neatly in the channels *c* in the cross-rails and corresponding 90 channels (not seen) in the side rail A', and of a length to reach considerably beyond the shoulders *s* in the cross-rails, one side of each of these arms being cut out, as at 6, so as to leave a shoulder, 7, which rests against a 95 stop-pin, 8, in each cross-rail.

In United States Letters Patent No. 374,187, granted to me on the 6th day of December, 1887, I illustrated and described an auxiliary screen designed to be used with doors larger 100 than the smallest. This screen consisted of a cross-rail constructed in two pieces, one of

said pieces being tongued on its inner side and the other correspondingly grooved, the pieces being held adjustably together by headed bolts and screw-threaded nuts, the 5 bolts passing through a hole and a slot in each piece, and attached to each piece was a strip of wire-cloth long enough to extend slightly beyond the middle, so that when the cross-rail was extended to its full width the meeting ends of the strips would slightly overlap. That auxiliary screen was adjusted in the side rails at the proper height for a door of the desired length and the wire-cloth was trimmed off at the bottom, so that it would 10 just rest on top of the top cross-rail of the door.

Instead of constructing the auxiliary screen as above stated, I now make the screen-rail E in one piece of the same length as cross- 20 rails B B', and tenon the ends, as at e, to adapt rail E to slide in grooves g, cut in the side rails, which grooves extend some distance below the upper cross-rail, B, which is slotted its whole length, as at b, the grooves being 25 larger above said rail than below it, as their lower portion is designed to receive the wire-cloth, F, which is provided on three of its edges with a thin metal binding, f, its upper edge being secured to the screen-rail E in any 30 suitable manner.

As before stated, in the manufacture of these screen-doors I make the side rails, A A' D, of a length suitable for the largest doors in common use, and then when a door smaller 35 than that size is required I adjust the auxiliary screen-rail E in the grooves g in the side rails A A' at the proper height for a door of the desired length and cut off the rails A A' D on a line with the upper side of the auxiliary 40 screen-rail, the screen F passing through the slot b in cross-rail B and resting in the lower portion of grooves g. The door can then be adjusted as to width by means of the sliding rail D, as above explained.

45 Having thus described my invention, what

I claim as new, and desire to secure by Letters Patent, is—

1. The combination, with side rails, A A', and cross-rails B B', rigidly framed together, and a screen secured in said frame, rail A' 50 being narrower and thinner than rail A, and one end of each of the cross-rails reduced to the thickness of rail A' and provided with guide-channels, of the L-shaped sliding side rail provided with laterally-extending arms 55 engaging said channels, whereby the sliding rail is adapted to slide over rail A' and over the reduced ends of the cross-rails, substantially as described.

2. The combination, with side rails, A A', 60 the latter narrower and thinner than the former, and cross-rails B B', provided with guide-channels, rigidly framed together, and a screen secured in said frame, of the L-shaped sliding side rail slotted at top and bottom, as described, headed bolts passed through said 65 slots and through rail A', said sliding rail being also provided with laterally-extending arms, each having a shoulder near its outer end and engaging said channels, and a stoppin in each cross-rail in front of the shoulder on the arm, substantially as described.

3. The combination, with the grooved side rails, A A', and the cross-rails B B', rigidly framed together, the rail B being slotted vertically its whole length, and a screen secured 75 in said frame, of the L-shaped sliding side rail adjustably secured to rail A', a rigid auxiliary cross-rail, and a screen attached to said rail, the auxiliary cross-rail being secured in 80 the grooves in rails A A' above cross-rail B, and its screen passing through the slot in said cross-rail and overlapping the fixed screen, substantially as described.

In testimony whereof I affix my signature 85 in presence of two witnesses.

WILLIAM HUGHES.
